UNITED STATES PATENT OFFICE.

MILLER REESE HUTCHISON, OF ORANGE, NEW JERSEY, ASSIGNOR TO LOVELL-McCONNELL MANUFACTURING COMPANY, A CORPORATION OF DELAWARE.

DIAPHRAGM-HORN.

1,094,403.

Specification of Letters Patent. Patented Apr. 21, 1914.

Original application filed May 11, 1911, Serial No. 626,487. Divided and this application filed May 31, 1912. Serial No. 700,789.

To all whom it may concern:

Be it known that I, MILLER REESE HUTCHISON, a citizen of the United States, and resident of Orange, in the county of Essex and State of New Jersey, have invented certain new and useful Improvements in Diaphragm-Horns, of which the following is a specification.

This application is a division of my prior application Serial No. 626,487 filed May 11th, 1911. In the said parent application I have shown various different ways which a diaphragm horn may be designed so that it will require somewhat less power to start it, and when running will give forth a sound of less harshness than that produced in a horn in which the actuator directly engages with the diaphragm or with a wear piece rigid therewith. By means of the various constructions shown I may produce a sound of less harshness and at the same time save wear and tear of the diaphragm by the use of a non rigid, more or less yieldable, elastic connection or coupling between the driver and diaphragm. This intermediate device when properly designed and arranged receives the rigid thrust of the driver and at inharmonious speeds partially absorbs and partially transmits to the diaphragm the energy thus supplied to it, while at harmonious speeds practically all of it is transmitted and little or none of it is used up in the elastic coupling device. In this way I somewhat lessen the abruptness with which the diaphragm is set in motion or the direction of its motion changed so that the quality of the sound produced is tempered according to the nature or extent of the yielding of which the connection is capable. Various different means for attaining this result are disclosed in the said prior application and in which the cushioning connection may be either coupled to the diaphragm or merely in contact therewith and in which the connection may assume various non rigid elastic forms.

My present invention involves that type in which there is a transversely flexible elongated member adjacent to one surface of the diaphragm but preferably not in contact with the vibrating portion except where it is secured thereto, preferably at or near the center at the latter. By having the driver contact with this cushioning member or a

wear piece on the latter at a point removed 55 from the point at which the cushioning device is secured to the diaphragm the force of the driver will be imparted to the diaphragm through the intermediate portion of the elastic connection by more or less modified 60 or tempered thrusts rather than by blows imparted directly to the diaphragm. The natural outward and return vibrations of the diaphragm may be completed or terminated with less interference and less abrupt 65 change by reason of the slight bending or yielding of the connecting member. This has advantages both as to power consumption, wear and tear, and quality of the note, especially at starting and stopping when the 70 thrusts of the driver may be out of synchronism with the diaphragm. I prefer to secure the connecting member to the diaphragm positively, thereby the more surely avoiding 75 any lost motion between it and the diaphragm so that scraping, rattling, pounding or direct blows on the diaphragm by the cushioning device are prevented and the diaphragm and the cushioning member vibrate as a unit. The wear piece or other portion 80 of the connecting member with which the driver contacts being more or less resiliently supported, it can give under the blows of the driver and thus the wear on it as well as the driver will be reduced. In the case of 85 powerful warning signals such as are now standard in the market, the wear and tear at these non-synchronous speeds is enormous as compared with the more natural synchronous speeds or harmonized speeds at which 90 the natural outward and return vibrations of the steel diaphragm tend to hold the motor, and I have discovered that the yielding interposed between the positive thrust of the driver and the diaphragm may be sufficient 95 to enormously decrease this wear and tear without being great enough to destroy the positiveness of the cam thrust or the governing action of the diaphragm upon the cam. Where there is a non-positive connection between the interposed member and the diaphragm or where the said member is too 100 springy there may result movements of such member independently of the diaphragm at the non-synchronous speeds, and also that the interposed member is liable to 105 vibrate in a different frequency from that of the diaphragm and this even at speeds

where the cam thrusts are at a rate harmonizing with the natural movements of the diaphragm. Hence I preferably avoid too great springiness as well as lost motion between the wear piece and the diaphragm so that any movements of the wear-piece independently of the diaphragm are small as compared with the diaphragm movements and with the cam forcing movements.

As stated in my parent application, Serial Number 626,487, above referred to, the diaphragm preferably has the qualities and method of operation described in my application, Serial Number 494,120, filed May 5th, 1909, that is to say the signal when driven by a suitable motor tends to be self-governing, so that the rotary driver tends to rotate at a speed which will give the note corresponding to a natural or resonant frequency of the bodily swing of the whole diaphragm, which of course may be modified by and accord with the natural frequency of a suitable selected resonator. In short, where the motor is of suitable power so that it is capable of varying its speed according to the work done in vibrating the diaphragm, any tendency of the rotary driver to speed up beyond harmonious speeds to inharmonious speeds causes the projections thereon to intercept the diaphragm projection sooner with the result that work done on the diaphragm increases in disproportionately greater ratios, with the result that the motor and driver are held substantially to harmonious speeds throughout wide variations in battery power. Substantially the same results are obtained in the present instance and are best insured when the resonator is properly constructed and when the diaphragm is of relatively thin steel.

The cushioning member is preferably connected to the diaphragm at or near the center of the latter so that the maximum vibration is imparted to the latter by a given displacement of the cushioning device and when it is in the form of a stiff spring with one end rigidly secured to the center of the diaphragm and the other end supported adjacent to the periphery of the diaphragm, the wear piece will be preferably mounted intermediate of the ends of the spring so that for a given movement of the center of the spring, the end of the spring at the center of the diaphragm, may be given a greater movement and impart the maximum vibration. When the cushioning member is constructed and arranged so that its range of yielding movement relatively to the diaphragm is small as compared with the total range of diaphragm movement or effective altitude of the cam projections of the driver the power lost will be at a minimum.

Having thus briefly described the general characteristics of my invention I shall proceed to a description of one embodiment

thereof, reference being had to the accompanying drawings, in which—

Figure 1 is a side elevation, partly in section, of a diaphragm horn embodying my invention and Fig. 2 is a horizontal section 70 through the case.

My invention relates solely to the means for imparting the vibrations to the diaphragm and may be embodied in horns or signals of various different characters. For purposes of illustration I have shown a resonator or projector 1 carried by the front section 2 of a diaphragm case. The diaphragm 3 is held between cork washers or the like 4, 5, by the marginal clamping portions 6, 7, of the front section 2 and the rear section 8 of the diaphragm case. The clamping is effected by screws 9, which pass through openings in the clamping portions of the case sections and in the gaskets and the marginal region of the diaphragm.

The rear section 8 of the case is formed to receive the rotary driver 10, which is shown as a disk provided with a plurality of peripheral cam projections. The axis of this rotary driver may be parallel to the diaphragm, as shown although this is not essential. Suitable means for rotating the driver at high speed is illustrated in the form of an electric motor 11, the armature shaft 12 of which is prolonged into the rear section of the diaphragm case, there carrying the rotary driver. The driver is preferably solidly mounted so as to deliver rigid thrusts to the cushioning connection 13, and to this end the bearing 14 of the rigid shaft 12 rigidly holds the shaft and is rigidly secured to the rear section of the diaphragm case. The bearing sleeve 14 has exterior cylindrical bearing upon the case at 14^a, 14^b, the axis of 105 the shaft being eccentric to said cylindrical bearing surfaces, so that rotary adjustment of the sleeve adjusts the cam to or from the diaphragm.

The connection 13 is in the nature of a 110 relatively stiff yet light spring tongue extending substantially parallel to the diaphragm along a radial line. The spring tongue is anchored at one point to the diaphragm and at another point to a stationary 115 part with the driver coacting with the tongue at an intermediate point. The outer end is preferably held between the clamping members at the margin of the diaphragm and is spaced from the diaphragm while the other end is slightly bent toward the diaphragm and securely anchored to the center thereof in any suitable manner as for instance by a rivet 25. A wear piece 18 is riveted to the tongue intermediate its end and the driver is placed in a corresponding position with reference to the diaphragm. The spring tongue operates as a lever in transmitting the thrust in a cushioned manner to the diaphragm. By reason of the 130

lightness of the tongue and the fact that it does not contact with the diaphragm along most of its length but may bend freely with the diaphragm, it does not interfere with the 5 harmonious coöperation of the driving and driven member. In operation, the amount of sound produced by this assemblage will approach that produced by a rigidly actuated horn, according to the stiffness of the 10 spring tongue and the extent to which its wear portion intercepts the path of travel of the cam projections. The less yielding the connection, the more does it directly transmit the thrust of the cam and the less should 15 be its normal projection into the path of movement of the cam projections. As the thrust of each projection begins and continues, the resultant motion is in part transmitted by the connection to the diaphragm 20 and in part spent in flexing the connection. For this reason the degree of interception of the path of travel of the projections by the wear portion of the connection may be greater than the interception in the case of 25 a wear piece fixed directly on the diaphragm. That is to say, other things being equal, the yielding connection has the effect of prolonging the time and reducing the intensity of each thrust. From this it naturally re- 30 sults that the diaphragm is displaced less abruptly and violently and that the sound is smoother and softer than in the case of a rigidly actuated signal. On the other hand the degree of interception of the path of 35 travel of the projections by the wear piece may be less than with the wear piece fixed on the diaphragm as the leverage and resiliency of the spring will give the diaphragm a sufficient initial thrust in starting the driver 40 that it will properly engage on the return vibration and continue to properly engage during the normal operation. Thus with this construction it is not necessary to have so delicate a relative adjustment of the 45 driver and wear piece.

Having thus described my invention, what I claim as new and desire to secure by Letters Patent is:

1. In an alarm or signal, a diaphragm, a 50 bar disposed closely adjacent to said diaphragm extending radially from the center to the periphery, said bar having a portion bent toward said diaphragm and tightly clamped thereto, the remainder of said bar 55 being spaced slightly from said diaphragm and having the other end clamped rigid therewith, a wear-piece on said bar, adjacent to but out of alinement with the axis of said diaphragm and a rotor having a series of 60 cam projections for successive engagement with said wear-piece, said bar being slightly resilient under conditions of use.

2. In an alarm or signal, a diaphragm, a bar disposed substantially parallel with and 65 closely adjacent to said diaphragm, but

spaced therefrom along the major portion of the length of said bar, means for clamping said bar to said diaphragm adjacent to the center of the latter, a casing including two clamping members, an annular washer, 70 means for rigidly holding said clamping members together with the said washer, the peripheral portion of said diaphragm and one end of said bar therebetween, and forcing means acting on said bar toward said diaphragm to impose on the latter a series 75 of bodily swings of the center portion thereof.

3. In an alarm or signal, a diaphragm, a thrust transmitting member including a resilient bar having one end rigidly clamped adjacent to the edge of the diaphragm and having another portion secured to the diaphragm at the center of the latter and an impact member for delivering thrusts to 80 said first-mentioned member at a point removed from the center of the diaphragm.

4. In an alarm or signal, a diaphragm, a spring having one end supported adjacent the periphery of the diaphragm and having 90 the opposite end secured to the diaphragm at the center of the latter, a wear piece on said spring intermediate of the ends of the latter and a rotary impact member having engagement with said wear piece. 95

5. In an alarm or signal of the class described, an elastic diaphragm having a substantially definite time period of free bodily swing, an elongated spring member tightly secured adjacent to the periphery of the 100 diaphragm, and also tightly secured to a central portion of the diaphragm, said spring member presenting a wearpiece spaced endwise from the portion secured to the diaphragm, the stiffness of said 105 spring member and the arrangement of said wearpiece being such that in full operation the movements of the wearpiece bear a definite relation to the natural swing of the diaphragm, in combination with a rotary 110 cam having projections formed and spaced to have a positive forcing engagement with said wear-piece, and a motor adapted to vary its speed in accordance with the work done on the diaphragm and of sufficient 115 power to start and drive said cam up to and at speeds causing cam contacts at intervals corresponding to and harmonizing with the movements of said wearpiece.

6. In an alarm or signal of the class described a relatively thin elastic metallic diaphragm, an elongated spring member having one portion tightly secured in fixed position at a point remote from the center of the diaphragm and having another portion maintained in fixed relation to a central portion of the diaphragm, said member presenting a wearpiece spaced along said spring member from the diaphragm forcing portion of the latter, the stiffness of said 120

- spring member and the relative arrangement of said wearpiece being such that in normal full-speed operation the movements of the wearpiece are harmonized with the to and fro bodily swing of the diaphragm, in combination with a rotary cam having projections formed and spaced to have a positive forcing engagement with said wearpiece through a portion of the movement and to permit another portion of the movement to be free elastic, and a motor adapted to vary its speed in accordance with the work done, and of sufficient power to start and drive said cam up to and at speeds causing cam contacts at intervals corresponding to and harmonizing with the natural swing of the vibratory parts.
7. In an alarm or signal of the class described, an elastic diaphragm having a substantially definite time period of bodily swing, a rotary cam and means for driving it up to a speed of synchronism of cam con-

tacts and diaphragm swings, in combination with an elongated element between the cam and diaphragm and having a portion tightly secured to a central part of the diaphragm and a cam engaging portion, said portions being spaced apart radially of the diaphragm and said cam engaging portion being spaced away from said diaphragm and slightly movable toward and from the same to cause and permit continuous bodily swing of the diaphragm with a cam push for every swing at normal working speeds but cushioning independent interfering movements occurring at sub-normal speeds.

Signed at Excelsior in the county of Hennepin and State of Minnesota this 22nd day of May A. D. 1912.
